R. B. SHERIDAN.

TRUCK FRAME.

APPLICATION FILED MAR. 13, 1913.

1,070,545.

Patented Aug. 19, 1913.

UNITED STATES PATENT OFFICE.

RICHARD B. SHERIDAN, OF CLEVELAND, OHIO, ASSIGNOR TO THE BROWN HOISTING MACHINERY COMPANY, OF CLEVELAND, OHIO, A CORPORATION.

TRUCK-FRAME.

1,070,545.

Specification of Letters Patent. Patented Aug. 19, 1913.

Application filed March 13, 1913. Serial No. 754,000.

To all whom it may concern:

Be it known that I, RICHARD B. SHERIDAN, a citizen of the United States, residing at the city of Cleveland, in the county of 5 Cuyahoga and State of Ohio, United States of America, have invented a new and useful Truck-Frame, of which a clear and exact description, with references therein to drawings that accompany and make a part 10 of the specification, is hereinafter fully set forth.

The more general use for the device in question will be as a movable support for the respective ends of the bridge-girders, or I-beams forming the track-ways of over-head cranes, ore lorries, or transfer cars, upon and along which trackways loads of various sorts are to be traversed. The supporting framework of the end trucks, in such cases, is subjected to a high degree of intensive strain, and it is of corresponding importance that the design of the same shall be such as to locate the center of the strain, in the supporting medium, at such point as will, as nearly 20 as possible, reduce all eccentric or indirect strains to a minimum. In the use of truck-frames of this class, headspace is generally of prime importance and, in consequence, the beam-girders referred to cannot usually be 25 mounted directly upon the top of the truck, but, in some manner, must be firmly connected thereto below the top, and as near to the rails upon which the truck is mounted as clearance requirements permit. Said girders are then sometimes butted up centrally 30 against the inner side or face of the truck-frames, and, in such relation, bolted against displacement when weight is applied; or, the truck-frame is made in two sections 35 which are fastened, by bolts, braces and rivets, to the opposite sides of the web of the I-beam or girder. In such forms of construction, besides the need of accurate milling, in each case, and, an undesirable amount 40 of special fitting, that is expensive as well as inconvenient in view of the usual conditions under which the crane is finally installed in its operative place, the weight of the beam 45 that is supported by the trucks, from the manner of its connection or relation to the truck-frame, is sure to set up a series of in-

direct or eccentric strains therein that it is important to avoid.

The purpose of the present invention is to afford a design for truck-frames of the class 55 referred to whereby the requirements of headspace for the supported trackways are minimized, the truck-frames themselves standardized, in an appreciable manner, to the various depths of beams, and abnormal 60 strains avoided or greatly reduced. All this is effected by a constructional plan for the frames that at the same time admits of the machining of all bearing surfaces thereof at the same operation, and whereby a truer 65 alignment is insured in shop practice.

In the drawings, Figure 1 is a side elevation of an end-truck with a track-member, in full lines, in place thereon, and, in dotted lines, the position of other such members 70 when of different depths, and similarly placed. Fig. 2 is a plan of Fig. 1 the beam members being removed. Fig. 3 is a view of Fig. 1 from beneath, said members with the truck wheels removed. Fig. 4 is an enlarged sectional view from within the frame of the truck toward a side of the supported end of the beam which latter is denoted by dotted lines. Fig. 5 is an overhead crane 75 provided with said trucks in place upon 80 their runways or rails. Fig. 6 is a plan of a portion of said runway with the beam and trucks of the crane in a convenient relative position to be hoisted simultaneously into place thereon, and, Fig. 7 is a side-view of 85 a truck-frame for a plurality of supported beams in position on the same.

In the drawings the frame proper comprises a single-piece, or casting 1, made up of a horizontal top-member 2, interrupted 90 or divided midway by a transverse slot or aperture 3, and, a bottom-member 4, consisting of a flat portion or seat 5, immediately below said aperture and upwardly inclined or flaring portions 6, 6 on either side of 5. 95 Said flaring portions of the member 4 respectively reach and are merged with the outer extremities of the top-member 2, and, together with the member last named, extend outwardly as and forming the respective ends of the frame. When a plurality of 100 beams are to be supported by the frame, as

Illustrated in Fig. 7, said flat portion of seat will of course be correspondingly extended in dimensions. These ends are vertically apertured or bifurcated, as at 7, 7, to a degree to permit the truck wheels 8, 8, to be operatively located within the apertures, with the frame resting upon and being supported by their respective axles which latter are duly journaled, in such position, to and beneath said ends, as indicated in the figures. The flat portion 5 of the lower or bottom-member 4 and the transverse aperture 3, should be of suitable dimensions to accommodate the lower flange of the I-beam to be supported by the truck, when the latter is resting on the portion 5 with the web of the beam projecting upwardly through said slot. It will be found advisable to make the top-member in a solid or entire piece, in the first instance, and then machine out the slot or aperture 3 to a standard width, which may correspond with the maximum web-thickness used in cranes of the sort. Shims or other special means may then be depended upon for the necessary narrowing of the slot to fit the webs of lesser measurements.

In Fig. 1, 10 represents an I-beam in place within the frame, and 11 and 12, in dotted lines, the relative position of other beams of different depths when similarly placed. To confine the beam against longitudinal displacement bolts 13, passing through the web and the top-member on each side thereof, are employed, and, further to this end, a dowel-pin 14 may be let into the bearing surface or portion 5, to fit in a corresponding hole on the under side of the beam's flange. Straightening members 15, on each side of the top member, and integral with the casting, extend from the aperture 3 to the member 4 below.

By the principle of construction above described, a truck-frame is produced which may be readily adapted, in the field or place of erection, to any size of beam web desired without riveting or other operation than bolting. By sliding the frames inwardly along the beam (Fig. 6) the latter may be hoisted directly to above the runways without interference of the trucks and with but a slight deflection of the beam itself from the normal with respect to said runways, whereupon, by turning the beam until its ends are above the runways, the trucks may be moved to such ends, the bolts 13 secured in their functioned place, and the process of erecting or assembling the crane be fully carried out. When a crane is thus assembled it is manifest that the beam will be securely held both in its upright and horizontal relation with respect to the trucks, the tension strains involved be cared for by the direct bearing of the beam upon the bottom-members 4, the compression strains by the stated bearing 65 of the upper members 2 against the opposite

sides of the web, and, the weight be sustained, as designed, without any abnormal or undue transmitted strains whatever.

What I claim and wish to secure by Letters Patent is:—

1. A truck-frame composed of a single piece, comprising a top-member having a transverse aperture of suitable dimensions to admit therein the web of the beam to be supported, a continuous member below said top-member, and end-portions, into which said members merge, of suitable construction to operatively engage the carrying wheels for said frame, substantially as shown and described. 70

2. A truck-frame, comprising a top-member having a transverse aperture of suitable dimensions to admit therein the web of the beam to be supported, a continuous lower member beneath and merging at its extremities into the top-member, and end-portions vertically apertured to receive the truck wheels for said frame, substantially as 85 shown and described. 80

3. A truck-frame comprising a top-member, a bottom-member integrally connected therewith, and end-portions suitably constructed to be brought into operative engagement with the carrying-wheels of said frame, said top-member being divided by a transverse aperture of suitable width to admit therethrough the web of the beams to be supported by the frame, substantially as 90 shown and described. 95

4. A truck for overhead cranes and similar constructions comprising the combination of a frame top-member, divided by a transverse aperture of suitable width to admit therethrough the web of the track-beam to be supported by said frame, a bottom-frame-member, integral with the top-member, having a seat for said beam below said aperture at a distance therefrom not greater than the depth of said web, and inclining upwardly on either side of said seat to and merging into said top-member, end-portions on said frame, together with carrying wheels for the frame operatively connected with said ends, substantially as shown and described. 100 105

5. A truck-frame comprising a top-member, a bottom-member integrally connected therewith, and end-portions suitably constructed to be brought into operative engagement with the carrying-wheels of said frame, said top-member having a plurality of transverse apertures of suitable width to admit therethrough the webs of the beams to be respectively supported by said frame, substantially as shown and described. 110 115

6. A truck for overhead cranes and similar constructions, comprising the combination of a top-frame-member, having a plurality of transverse apertures of suitable width to admit therethrough the webs of the 120 125

track-beams to be respectively supported by said truck, a bottom frame-member, integral with the top-member, having a flat portion for said beams below said apertures at a distance therefrom not greater than the depth of the webs, and inclining upwardly on either side of said flat portion to and merging into said top-member, end-portions at

the frame of said truck, together with carrying-wheels for the truck operatively connected with said end portions, substantially as shown and described. 10
